UNITED STATES PATENT OFFICE.

CHARLES L. BUDDENBOHN AND WILLIAM SPEER, OF BALTIMORE,
MARYLAND.

FIRE-ESCAPE.

SPECIFICATION forming part of Letters Patent No. 624,432, dated May 2, 1899.

Application filed December 22, 1898. Serial No. 700,043. (No model.)

To all whom it may concern:

Be it known that we, CHARLES L. BUDDEN-
BOHN and WILLIAM SPEER, citizens of the
United States, residing at Baltimore city,
5 State of Maryland, have invented new and
useful Improvements in Fire-Escapes, of
which the following is a specification.

Our invention relates to that class of fire-
escapes in which are employed a rotating
10 drum, a lowering-rope thereon, and springs
for resisting the downward movement of the
rope, the object of the same being to provide
an automatic governor or brake for controlling
the downward movement of the rope
15 when a passenger is supported thereby, the
same being so constructed and arranged that
it will act with greater or less force, accord-
ing to the weight of the passenger.

A further object of the invention is to pro-
20 vide means for automatically laying the rope
evenly and smoothly upon the drum and pre-
venting the slipping of the same from the
drum.

Other objects and advantages of the inven-
25 tion will hereinafter appear, and the novel
features thereof will be set forth in the ap-
pended claims.

In the drawings forming part of this speci-
30 fication, Figure 1 represents a front elevation
of our improved fire-escape. Fig. 2 is a side
elevation of the same. Fig. 3 is a vertical
section taken on the line 3 3 of Fig. 2. Fig.
35 4 is a section on the line 4 4 of Fig. 1. Fig.
5 is a detail perspective view of the brake
plate or shoe, and Figs. 6 and 7 represent
views of other details.

The frame of the device is made up of a
base or back plate 1, a top or face plate 2,
and an intermediate supporting-plate 3, all
40 secured together in parallel relation and held
spaced apart by the rods or bolts 4 4. The
said frame and the parts carried thereby are
adapted to be suspended from any suitable
point by the ring or hook 5, which embraces
45 the bar 6, connecting the plates 1 and 2 at
their upper ends. The said bar is provided
with a plurality of notches 7 for the reception
of said ring, and in this way provision is
50 made for adjusting the position of the device
relative to its point of suspension.

Mounted to turn in bearings in the plates

1 and 2 is a central shaft 8, having a pinion
9 secured to the outer end thereof and having
mounted thereon adjacent to the plate 1 a
winding-drum 10, the side plates 11 and 12 of 55
which project beyond the intermediate por-
tion and form guide-flanges for the lowering-
rope 13, which is wound thereon. The outer
plate 11 of said drum has secured to it a cir-
cular rack 14, which meshes with a pinion 15, 60
loose on the shaft 16 and having a clutch
connection with a disk 17, fast on said shaft
16, so that when said pinion is rotated in one
direction it will turn said shaft, and when it
is rotated in the opposite direction said shaft 65
will remain stationary. The shaft 16 has se-
cured to it a second pinion 18, meshing with
an idle pinion 19, which latter in turn meshes
with a pinion 20, fast on a shaft 21, carrying
a large cog-wheel 22. The said cog-wheel 22 70
engages and transmits its motion to a toothed
sleeve 23, loose upon the shaft 8 and having a
clutch connection with a second sleeve 24,
provided with a series of radially-extend-
ing arms 25. Instead of this clutch connec- 75
tion between these sleeves, however, the
same may be made integral or be secured to-
gether in any other suitable manner. Sur-
rounding the sleeve 24 and adapted to ro-
tate therewith, but capable of longitudinal 80
movement independent thereof, is a brake
plate or shoe 26, designed to frictionally en-
gage the outer plate 11 of the drum 10. The
said plate or shoe is formed with wings 27 27,
having flanges 28 28 upon their outer surfaces 85
provided with inclined outer edges adapted
to be engaged by the segmental brake-actu-
ating blocks 29 on the radial arms 25 of the
sleeve 24. The said blocks are thrown out-
wardly by centrifugal force upon the rapid 90
rotation of the sleeves 23 and 24, and their
outward movement is resisted and partially
impeded by the coil-springs 30, which sur-
round the arms 25 and engage at one end said
blocks and at the opposite end nuts 31, screwed 95
upon the ends of said arm. Said nuts further
serve as a means for adjusting the tension of
the springs 30.

From the foregoing description it will be
seen that as the rope 13 unwinds, due to the 100
weight of a passenger thereon, the drum 10
will be rotated and its motion will be trans-

mitted through the system of multiplying-gearing described to the sleeves 23 and 24, and the latter will be rotated very rapidly. This causes the brake-actuating blocks 29 to 5 be thrown outwardly by centrifugal force and brought into engagement with the inclined edges of the flanges 28 on the brake-shoe 26, throwing said brake-shoe inwardly into contact with the plate 11 of the winding-drum. 10 This serves to check the movement of said drum and prevents the passenger from descending at a dangerous speed. It will of course be noted in this connection that the heavier the passenger the greater will be the 15 initial movement of the drum 10 and the parts operated thereby and the greater will be the constant tendency of said parts to turn rapidly; but the greater the movement of the drum or its tendency to move the greater will 20 be the pressure exerted by the brake-shoe on the drum. The result is that whatever the weight of the passenger the rapidity of the descent will remain constant.

In connection with the parts above described we employ a pair of tension-springs for the drum, which also serve to rewind the lowering-cord when the weight of the passenger has been removed. These springs 32 are located in front of the face-plate 2 and between 25 said face-plate and a supplemental plate 33, held in place upon the frame by rods or standards 34. The said springs are secured at one end to bars 35, connecting the plates 2 and 33, and are attached at their other ends 30 to rolls or drums 36, mounted to turn in bearings in the said plates. The rolls 36 have secured to their inner ends the cog-wheels 37, which mesh with the pinion 9 on the end of the shaft 8. The movement of said shaft, 35 caused by the outward movement of the lowering-rope 13, causes, through the gearing described, the rotation of the rolls 36 in a direction to wind up the springs 32. When the weight upon the lowering-rope is relieved, the 40 springs will cause a rotation of the rolls 36 in the reverse direction and a consequent rotation of the drum 10 in a direction to wind up the cord 13 thereon. It will be noted, however, that when the said drum moves in a direction to wind up the cord the pinion 15 slips 45 over the surface of the disk 17, and consequently no movement will be imparted in a reverse direction to the gearing between said pinion and the sleeves 23 and 24, carrying the 50 brake-actuating mechanism. Said mechanism therefore remains at rest and inoperative, except when the lowering-rope is being wound.

The rope-laying mechanism employed consists of a laterally-movable sleeve, ring, or eye 37^a, located between and guided by the parallel rods or bars 38, connecting the plates 1 and 2 at their lower ends, a bell-crank lever 39, fulcrumed in a bracket 40, depending from 55 an arm on the plate 2, a link connecting one arm of said bell-crank lever with the sleeve 37^a, and means for rocking said bell-crank

lever automatically during the rotation of the drum 10 in one direction. The rope 13 extends through the sleeve 37^a and is provided 70 upon its outer free end with a strap, sling, or other form of harness, by means of which the passenger may secure and retain his hold upon the rope. As the said sleeve is moved in one direction or the other across the drum 10 it 75 carries with it said rope, and the latter is guided first to one side and then to the other of said drum and thereby caused to wind smoothly and evenly thereon. The means for rocking the bell-crank lever 39 to cause 80 the back-and-forth movement of the sleeve 37^a consists of a pinion 41, meshing with one of the cog-wheels 37 and loose upon, but having a clutch connection with, a shaft 42, mounted in a bracket-arm on the main frame, a disk 85 43, fast on said shaft, and a link 44, eccentrically connected to said disk and pivoted to the outer arm of the bell-crank lever 39. The clutch connection between the pinion 41 and the shaft 42 consists of an inwardly-spring- 90 pressed pin or dog 45 and a shoulder 46 on the shaft, by which construction said pinion will be caused to engage and rotate said shaft when moved in one direction and will slip freely thereon when moved in the other direction. When the lowering-cord is being 95 unwound from the drum 10, the pinion 41 will be moved in the direction of the arrow in Fig. 7. When, however, said cord is relieved from the weight of the passenger thereon, the springs 32 act to rotate the drum in a direction to wind the cord thereon and the pinion 41 is turned in a direction opposite that which it formerly had, the result being that the shaft 42 and the disk 43, carried thereby, 100 is turned with said pinion and through the link 44 the bell-crank lever 39 is rocked. This movement of the bell-crank lever causes a lateral back-and-forth movement to be imparted to the sleeve 37^a and the rope 13, passing therethrough, with the effect of causing the said rope to be laid in even coils upon the 105 drum 10.

What we claim as our invention is—

1. The combination with a drum, of a rotatable and longitudinally-movable brake for controlling the movement of said drum, and means actuated by the speed of movement of said drum for automatically throwing said 115 brake into operation.

2. The combination with a drum, of a brake-shoe for controlling the movement of said drum provided with laterally-extending inclined or wedge-shaped engaging surfaces, and brake-actuating devices adapted to be 125 thrown outwardly by centrifugal force to engage and slide upon the inclined surfaces of said shoe, as and for the purpose set forth.

3. The combination with a drum, of a rotatable and longitudinally-movable brake-shoe 130 adapted to engage said drum, and provided with inclined or wedge-shaped projections, and brake-actuating devices adapted to be thrown outwardly by centrifugal force to en-

gage the inclined projections on said shoe, as and for the purpose set forth.

4. In a fire-escape, a drum upon which the lowering-cord is wound, a rotatable and longitudinally-movable brake-shoe adapted to engage said drum, inclined or wedge-shaped flanges on said shoe, a sleeve on the drum-shaft rotated by said drum, radially-extending arms on said sleeve, and brake-actuating blocks carried by said arms and adapted to be thrown outwardly by centrifugal force to engage the flanges on said shoe, as and for the purpose set forth.

5. In a fire-escape, a drum upon which the lowering-cord is wound, a sleeve loosely mounted on the drum-shaft intermediate multiplying - gearing between said drum and sleeve, through which said sleeve is rotated by said drum, a brake-shoe carried by said sleeve but capable of independent longitudinal movement and adapted to engage said drum, inclined projections on said shoe, radially-extending arms on said sleeve, and brake-actuating blocks on said arms adapted to be thrown outwardly by centrifugal force to engage said projections, as and for the purpose set forth.

6. In a fire-escape, a drum upon which the lowering-cord is wound, a rotatable longitudinally-movable brake-shoe adapted to engage said drum, inclined or wedge-shaped projections on said shoe, a sleeve on the drum-shaft rotated by said drum, radially-extending arms on said sleeve, brake-actuating blocks carried by said arms and adapted to be thrown outwardly by centrifugal force to engage said projections, and springs for resisting the outward movement of said blocks, as and for the purpose set forth.

40 7. In a fire-escape, a drum upon which the lowering-cord is wound, a rotatable and longitudinally-movable brake-shoe adapted to engage said drum, inclined or wedge-shaped projections on said shoe, a sleeve on the drum-shaft rotated by said drum, radially-extending arms on said sleeve, brake-actuating blocks carried by said arms and adapted to be thrown outwardly by centrifugal force to engage said projections, springs for resisting

the outward movement of said blocks, and means for regulating the tension of said springs, as and for the purpose set forth.

8. The combination with a drum and a cord adapted to be wound thereon, of cord-laying mechanism comprising a laterally-movable guide for the cord, a rocking lever connected to said guide, and connections between said drum and said lever, whereby the rotation of the former is adapted to operate the latter.

55 9. The combination with a drum and a cord adapted to be wound thereon, of cord-laying mechanism comprising a laterally-movable guide sleeve or ring through which the cord passes, a bell-crank lever, a link connecting said sleeve with one arm of said bell-crank lever, a rotary shaft operated through suitable connections with said drum, and a link eccentrically connected to said shaft at one end and to the other arm of said bell-crank lever at the other end.

60 10. In a fire-escape, a drum, a lowering-cord wound thereon, springs for resisting the movement of said drum in one direction, and for actuating it in the other direction to wind the cord thereon, and cord-laying mechanism comprising a laterally-movable guide sleeve or ring through which the cord passes, a bell-crank lever, a link connecting said sleeve with one arm of said lever, a shaft, a 75 disk fixed thereon, a link eccentrically connected to said disk at one end, and to the other arm of said lever at the other end, and a pinion operated by said drum and having a clutch connection with said shaft, whereby, 80 said rope-laying mechanism will be thrown out of operation, when the lowering-cord is being unwound and into operation when said cord is being wound.

85 In testimony whereof we have hereunto set 90 our hands in presence of two subscribing witnesses.
